Des. 241,800
Patented Oct. 12, 1976

241,800

MIRROR

Lawrence H. Johnson, 944 King George Way, El Dorado Hills, Calif. 95630, and Leslie B. Korner, 1908 Manzanita Way, West Sacramento, Calif. 95691

Filed May 24, 1974, Ser. No. 473,007

Term of patent 14 years

Int. Cl. D6—07

U.S. Cl. D6—234

Fig. 1

Fig. 2

Fig. 3

Fig. 4

Fig. 5

Fig. 6

FIG. 1 is a front, top and right side perspective view of a mirror, showing our new design;

FIG. 2 is a right side elevational view in unfolded position, the left side being a mirror image thereof;

FIG. 3 is a top plan view thereof;

FIG. 4 is a bottom plan view thereof;

FIG. 5 is a front elevational view thereof; and,

FIG. 6 is a rear elevational view thereof.

We claim:

The ornamental design for a mirror, as shown and described.
